SOUND DEVICE FOR FLUID BOILERS

Max Mueller, New York, N. Y.

Application January 27, 1938, Serial No. 187,168

3 Claims. (Cl. 116—67)

This invention relates to new and useful improvements in a sound device for assisting in preventing heated fluids from boiling over.

More specifically the invention proposes the construction of a sound device having a bottom hollow face and engageable into a saucepan or other cooking dish or pot, and beneath which some of the fluid being heated may pass so as to reach the boiling point before the remainder of the fluid in the saucepan, to cause the sound device to be raised by the accumulated steam of the liquid boiling there-beneath so that it will drop back to its normal position after the steam escapes to cause a succession of rapid knocking alarm noises as it hits the bottom.

Still further it is proposed to construct the sound device with hollows of different compasses in the faces thereof, for controlling the amount of time necessary before the sound device is set into operation by the escaping steam.

Still further it is proposed to construct the sound device from an outer annular section and a central disc section adjustably mounted within the outer annular section for increasing or decreasing the compass of the hollow portions formed therein.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a sound device constructed according to this invention.

Fig. 2 is a view taken through the center of the saucepan showing the manner in which the sound device is to be used.

Fig. 3 is an elevational view of a modification of the invention.

Fig. 4 is a sectional view taken on the line 4—4 of Fig. 3.

Fig. 5 is an elevational view of a still further modification of the invention.

Fig. 6 is a sectional view on the line 6—6 of Fig. 5.

Fig. 7 is an enlarged detailed view of a portion of Fig. 6.

The sound device for preventing heated fluids from boiling over, according to this invention, consists of a shallow body 10 for location in a container 11 in which a fluid 12 is to be heated, and said body is adapted to rest freely on and extend across the bottom 11a of the saucepan, or

pot 11. The shallow body 10 has a shallow bottom face 13 beneath which some of the fluid 12 is adapted to collect. The body 10 has a passage 14 in one of its sides connecting the compass beneath the hollow bottom face 13 with the exterior through which the fluid 12 may pass. Thus upon heating the receptacle 11 through the bottom 11a thereof the fluid 12 beneath the body 10 will start boiling before the remaining fluid within the container 11, and rattle the body 10 to emit a warning sound.

The shallow body 10 may be constructed of hard material such as china, composition, metal, etc. Its top face is also provided with a hollow 15 having a compass of different capacity than that of the bottom hollow 13. A passage 16 connects the hollow 15 with the exterior of the hollow body 10 making it possible to rest the hollow body 10 on the bottom 11a of the container 11 with either face downwards and still permit the fluid 12 to pass therebeneath.

The operation of the device is as follows:—

When it is desired to heat fluids the hollow body 10 is rested within a container or pot 11 with either the hollow 13 or the hollow 15 adjacent the bottom 11a thereof. Then the container 11 is filled with the desired amount of fluid to be heated and a portion thereof will pass through the openings 14 or 16 to connect with either the hollow 13 or the hollow 15, depending upon which one is adjacent the bottom 11a. Then when heat is applied to the bottom 11a, the fluid 12 located within the hollow resting adjacent the bottom, will reach the boiling point before the remaining fluid 12 within the container 11.

As the fluid within the hollow body reaches the boiling point the steam created by the boiling fluid will attempt to escape and rush toward the opening connecting the hollow body with the remaining area of the container 11. As this steam attempts to pass through the opening it will slightly lift the hollow body from the bottom 11a. When the steam escapes the hollow body will again drop back to its normal position causing it to knock against the bottom 11a. As the boiling continues the rising and falling of the hollow body 10 will become more rapid until it reaches a point where it becomes a continuous rattle.

According to the modification shown in Figs. 3 and 4, the hollow body 10' is constructed of a slightly different shape than shown in the foregoing figures. The portion of the hollow body 10' between the hollows 13 and 15 has a concave top surface and a convexed bottom surface to

increase the compass of the top hollow 15 and decrease the compass of the bottom hollow 13. In other respects this form of the invention is similar to the previous form.

- 5 According to the modification shown in Figs. 5-7, the hollow body 10" is constructed of separate sections consisting of an outer annular section 10^a and a central disc section 10^b. The periphery of the central disc section 10^b is formed 10 with a groove 17, and a resilient wire ring 18 extends around the periphery of the central disc section 10^b and partially into the groove 17. The inner wall of the outer annular section 10^a is provided with a number of grooves 19. The 15 wire 18 is adapted to engage one of the grooves 19 for holding the central disc section 10^b in various adjusted positions with relation to the top and bottom edge portions of the outer annular section 10^a. The wire 18 has its ends 20 18^a spaced away from each other forming a space 20 therebetween which permits these ends to be urged together when the center disc section 10^b is being moved from one groove 19 to another groove 19.

- 25 The operation of this form of the invention is as follows:—

When it is desired to increase or decrease the compass of either the top hollow 15 or the bottom hollow 13 it is merely necessary to move the 30 central disc section 10^b either upwards or downwards for increasing or decreasing the desired hollow. In other respects this form of the invention is similar to the previous forms.

The openings 14 and 16 may be of any suitable size and shape, i. e. rectangular, round, etc.

While I have illustrated and described the preferred embodiments of my invention, it is to be understood that I do not limit myself to the precise constructions herein disclosed and the right 40 is reserved to all changes and modifications coming within the scope of the invention as defined in the appended claims.

Having thus described my invention, what I claim as new, and desire to secure by United 45 States Letters Patent is:—

50 1. A sound device for indicating that the boiling point of a heated fluid has been reached, comprising a shallow body for location in a container in which a fluid is to be heated and adapted to rest freely on and extend across the bottom thereof, and having a hollow bottom face beneath which some of said fluid is capable of collecting, and said body having a passage

connecting the compass beneath said bottom face with the exterior thereof through which said fluid may pass, whereby upon heating of the receptacle through the bottom thereof the fluid beneath said body will start boiling before other parts and rattle said body to make a warning sound, said body comprising an outer annular section and a central disc section vertically adjustably mounted thereon.

2. A sound device for indicating that the boiling point of a heated fluid has been reached, comprising a shallow body for location in a container in which a fluid is to be heated and adapted to rest freely on and extend across the bottom thereof, and having a hollow bottom face beneath which some of said fluid is capable of collecting, and said body having a passage connecting the compass beneath said bottom face with the exterior thereof through which said fluid may pass, whereby upon heating of the receptacle through the bottom thereof, the fluid beneath said body will start boiling before other parts and rattle said body to make a warning sound, said body comprising an outer annular section and a central disc section, and means 25 for vertically adjustably mounting said central disc section within said outer annular section.

3. A sound device for indicating that the boiling point of a heated fluid has been reached, comprising a shallow body for location in a container in which a fluid is to be heated and adapted to rest freely on and extend across the bottom thereof, and having a hollow bottom face beneath which some of said fluid is capable of collecting, and said body having a passage connecting the compass beneath said bottom face with the exterior thereof through which said fluid may pass, whereby upon heating of the receptacle through the bottom thereof the fluid beneath said body will start boiling before other parts and rattle said body to make a warning sound, said body comprising an outer annular section and a central disc section, and means 30 for vertically adjustably mounting said central disc section within said outer annular section, 40 comprising an annular ring engaging around the periphery of said central disc section and partially into a groove formed therein, said ring being adapted to engage one of a plurality of grooves formed in the adjacent inner face of said outer annular portion for holding said disc section in its adjusted positions.

MAX MUELLER.
